US00D616936S

(12) **United States Design Patent**
Liu

(10) **Patent No.:** **US D616,936 S**
(45) **Date of Patent:** ** *Jun. 1, 2010

(54) **COMBINATION PEN AND LASER POINTER**

(75) Inventor: **Liang Liu**, Ningbo (CN)

(73) Assignee: **Beifa Group Co., Ltd.**, Ningbo (CN)

(*) Notice: This patent is subject to a terminal disclaimer.

(**) Term: **14 Years**

(21) Appl. No.: **29/334,154**

(22) Filed: **Mar. 20, 2009**

(30) **Foreign Application Priority Data**

Oct. 9, 2008 (CN) 2008 3 0146720

(51) **LOC (9) Cl.** **19-06**

(52) **U.S. Cl.** **D19/49; D19/36**

(58) **Field of Classification Search** ..... D19/35, D19/36, 41-51, 53-57; 24/11 F, 11 P, 11 R; 401/34, 35, 52, 99, 104-109, 192, 195, 196; D26/37

See application file for complete search history.

(57) **CLAIM**

The ornamental design for a combination pen and laser pointer, as shown and described.

DESCRIPTION

FIG. 1 is an upper front right perspective view of a combination pen and laser pointer showing my new design;

FIG. 2 is a left side elevation view thereof;

FIG. 3 is a top plan view thereof;

FIG. 4 is a front elevation view thereof;

FIG. 5 is a right side elevation view thereof;

FIG. 6 is a bottom plan view thereof; and,

FIG. 7 is a rear elevation view thereof.
